US0D1114408S

(12) **United States Design Patent** (10) **Patent No.:** **US D1,114,408 S**
(45) **Date of Patent:** **** Feb. 17, 2026**

(54) **PET TOY**

(71) Applicant: **WOOF PET INC.**, Denver, CO (US)

(72) Inventor: **Daniel Haarburger**, Boulder, CO (US)

(73) Assignee: **Woof Pet Inc.**, Denver, CO (US)

(**) Term: **15 Years**

(21) Appl. No.: **35/003,078**

(22) Filed: **Jun. 7, 2023**

(80) **Hague Agreement Data**

Int. Filing Date: **Jun. 7, 2023**

Int. Reg. No.: **DM/230969**

Int. Reg. Date: **Jun. 7, 2023**

Int. Reg. Pub. Date: **Jun. 7, 2024**

(51) **LOC (15) Cl.** **30-12**

(52) **U.S. Cl.**

USPC **D30/160**

(58) **Field of Classification Search**

USPC D30/160, 199; D21/597, 606, 607, 608, D21/650, 656; 119/707, 709

CPC ... A01K 15/025; A01K 15/026; A01K 15/027
